MAP HANGER

Johnse H. Beck, Indianapolis, Ind., assignor to
 The Geo. F. Cram Company, Indianapolis, Ind.,
 a corporation of Illinois

Application April 10, 1939, Serial No. 267,155

6 Claims. (Cl. 248—215)

The present invention relates to improvements in apparatus for providing adjustable mountings for maps, display sheets or other indicia.

My invention is primarily adapted for the support of maps, display sheets, and the like, in schools, and the invention has for one of its objects that of providing adjustable supporting means adapted to be mounted at the top of a blackboard or on the wall, or in like position, for the supporting of display maps and the provision of means whereby the map supporting members may be adjusted along the face of the wall or blackboard and, when not in use, may be turned back to permit the mounting of other display means without moving or disturbing the position of the map supporting members.

For the purpose of disclosing my invention, I have illustrated an embodiment thereof in the accompanying drawing, in which:

Fig. 1 is a front elevation of map supporting means embodying my invention;

Fig. 2 is a sectional view on the line 2—2, showing a map roller support hung thereon;

Fig. 3 is a sectional view showing the supporting clips turned back; and

Fig. 4 is a sectional view showing a different type of map roll supporting frame which may be supported on my structure.

In the embodiment of the structure illustrated in the accompanying drawing, I provide a channel-shaped molding strip 1 which is preferably adapted to be secured to a molding 2, generally the molding which surrounds a blackboard. The bottom forwardly extending leg 3 of this molding strip is provided with an upturned lip 4 and the upper leg 5 of the molding strip is extended a substantial distance beyond that of the bottom leg and has upwardly extending therefrom a rail 6. The upper end of this rail has a reversed curve or bend 7 to provide a hooked lip 10 on which is adapted to be supported a plurality of map-supporting members 8. The molding strip is preferably formed of relatively thin sheet metal and is made of suitable lengths, generally in commercial practice about 6 feet long. Inserted in the channel member 1 are relatively short blocks 9 of rubber, cork, linoleum or like material, to provide a backing for the reception of thumb tacks, pins or the like. The molding strip is secured in position on the molding 2 by suitable screws 10 which pass through slots 11 in the edges of the molding strip and these screws likewise serve to hold the blocks 9 in position. Interposed between the screws and the blocks through which the screws pass are suit-

able washers or holding plates 12. Due to the fact that the openings in the molding strip 1 through which the holding screws 10 pass, are in the forms of slots, it is quite easy to secure 5 multiple lengths of the molding strip in position by causing the two ends to abut and passing the screw through the slotted ends with the washer overlapping the abutting ends as shown in Fig. 1.

Each of the clips 8 comprises a plate 13 having a rearwardly extending neck 14 from which there is adapted to project an upwardly extending arm 15 having a rearward curved hooked end 16 provided with an inturned lip 17. This hooked end is adapted to be secured over the hooked portion 7 of the molding strip with the inturned lip 17 fitting under the edge of the reversely curved hooked portion of the molding strip. Secured to the neck 14 and adapted to extend upwardly is a supporting hook 18 from 15 which the different articles may be hung and formed in the face of the supporting member is a vertically disposed elongated slot 19 terminating at its upper end in an angularly disposed enlarged opening 20. The plate 13, as 20 will be observed in Fig. 2, is adapted to be inclined slightly inwardly toward the molding 2.

In addition to the blocks 9 and the supporting members heretofore described, I may also provide one or more spring clips 21 adapted to be 25 secured between the molding strip and the molding 2 by the same screws which hold the molding strip in position. The upper portion of this spring clip is provided with openings through which the screws 10 may pass.

As illustrated in Fig. 2, one type of map supporting member may be secured in position. This type of supporting means preferably comprises a channel member 22, the top rear leg of which is provided with spaced apart openings 23 and the channel member supporting roller brackets 24. In order to support the roller frame in position, this frame is hooked over a pair of spaced apart supporting members 8, the hooks 18 being adapted to pass through the openings 23.

Another type of roller supporting bracket may also be supported from the structure heretofore described. In this type of bracket, a bar having bracket ends for supporting a roller map is provided with rearwardly extending spaced apart headed members 25. These headed bolts or screws or members may be inserted in the enlarged openings 20 in the face of the plate 13 and dropped down into the restricted slot 19.

which will receive the shank of the headed members and retain the structure in position.

Due to the inter-engaging hooks on the supporting members 8 and on the channel member 1, the supporting members 8 are adjustably supported on the channel member. When dropped in supporting position, the frictional engagement between the curved portion 16 on the supporting member and the curved portion 7 on the channel member is such as to practically lock the supporting members 8 against movement. At the same time, if it is desired to adjust the supporting members along the channel member, by simply slightly raising the supporting member at its lower end, the locking engagement is broken and the member may be slid along the molding strip. Furthermore, due to the interlocking structure, the supporting member may be raised or tilted upwardly, as shown in Fig. 3, and will remain in this position out of the way so that full advantage of the blocks 9 may be taken. Furthermore, while the supporting members 8 are readily adjusted along the molding strip, they cannot be readily removed from the molding strip to thereby become lost or misplaced.

If it is desired, a cutaway portion 26 may be provided in the rearwardly extending hook portion of the rail 7 to permit the removal of the supporting clips from the rail. Preferably, only one such cutaway portion is provided in each molding strip length and it is to be noted that with the structure assembled on the wall, this cutaway portion is not readily noticeable.

My structure is particularly adapted for use in schools and the like, and by the provision of the spring clips 21, one form of bulletin or sheet may be secured in position thereon. By the provision of the cork blocks 9, another form of indicia or material may be mounted in position without interfering with the mounting of the first form supported in the clips and by the provision of the sliding hooks still another form of indicia in the way of maps or the like may be mounted thereon without in any way interfering with the mounting of the structures heretofore described. Furthermore, it is obvious that in order to obtain access to portions of the cork or other soft material blocks 9, it is not necessary to slide the supporting clips out of position as these may be raised and will stay in the raised position until manually moved down.

The supporting bracket illustrated in Fig. 4 lends itself, together with the slots 19 in the supporting clips, to what has heretofore been termed in the trade, as a straight roll mounting. It will be noted that the headed studs 25 are relatively close together on the roll supporting frame and when these studs are hooked in a pair of clips which are likewise relatively close together, the bracket as a whole may rock on the support so that the roller for the map or like structure will

always seek a true horizontal position, thereby preventing crooked rolling of the map on the roller when used.

I claim as my invention:

- 5 1. In a supporting structure for maps or the like, a molding strip adapted to be secured to a wall and having an upwardly projecting rail provided with a rearwardly extending lip and a suspension clip slidably mounted on said strip, including a rearwardly extending hooked lip adapted to engage over said rearwardly extending molding lip and having in its face an elongated vertical slot terminating in its upper end in an enlarged opening.
- 10 2. In a supporting structure for maps or the like, a molding strip adapted to be secured to a wall having an upwardly projecting rail provided with a rearwardly extending lip and a suspension clip slidably mounted on said strip, including a rearwardly extending hooked lip adapted to engage over said rearwardly extending molding lip and having means thereon for receiving and supporting a map roller bracket.
- 15 3. In a supporting structure for maps or the like, a molding strip adapted to be secured to a wall and having an upwardly projecting rail provided with a rearwardly extending lip and a suspension clip slidably mounted on said strip, including a rearwardly extending hooked lip adapted to engage over said rearwardly extending molding lip and having mounted thereon a supporting hook.
- 20 4. In a supporting structure for maps or the like, a molding strip adapted to be secured to a wall and having an upwardly projecting rail provided with a rearwardly and downwardly curved lip and a suspension clip slidably mounted on said strip, including a rearwardly extending hooked lip adapted to engage over said rearwardly extending molding lip, said hooked lip having a forwardly extending projection adapted to engage beneath the rail lip.
- 25 5. In a support for maps and the like, a supporting rail adapted to be secured to a wall in spaced relation thereto and having a rearwardly extending lip and a suspension clip having a rearwardly extending hook provided with a portion adapted to engage under said lip, the distance between the wall and the rear edge of the rail lip being less than the width of said hook to thereby prevent the removal of said clip after the same has been positioned on said rail.
- 30 6. In a support for maps and the like, a supporting rail having a rearwardly extending lip and a suspension clip having a downwardly extending flange provided with a forwardly extending lip engaged under said rail lip to prevent removal of the clip from the rail while permitting relative movement between the rail and the clip.

JOHNSE H. BECK.
